RF DEVICE WITH ISOLATED ANTENNAS

The invention relates to the field of radiofrequency (RF) devices having a plurality of antennas. The invention applies in particular when the antennas operate in frequency bands that are adjacent or indeed similar.

BACKGROUND OF THE INVENTION

Certain recent pieces of electrical equipment, e.g. residential gateways, have a plurality of antennas in order to transmit and receive RF signals in different frequency bands. In order to limit interference between the antennas, it is appropriate to ensure that said antennas are correctly isolated from one another. This is particularly critical when the frequency bands used by a single piece of equipment are adjacent (e.g. 5 gigahertz (GHz) Wi-Fi and 6 GHz Wi-Fi), or indeed similar.

It is known to incorporate filter means, e.g. comprising analog electronic components, in the transmit and receive channels for RF signals. Nevertheless, such a solution has an impact on the transmitted or received RF signals regardless of their directions of propagation. Furthermore, that solution generally presents performance that is poor when the frequency bands are adjacent.

Also known are diversity techniques, e.g. making use of space diversity, of polarization diversity, or indeed of radiation pattern diversity. Nevertheless, the performance of those techniques is generally limited when they are implemented in a piece of equipment that is compact. In particular, they do not make it possible for RF signals to be propagated omnidirectionally in multiple-input multiple-output (MIMO) RF systems making use of frequency bands that are adjacent.

It is also known to make use of isolating elements such as screens, reflectors, or indeed absorbers, made out of one or more pieces of metal. Nevertheless, isolating elements made in that way provide poor performance when they are incorporated in a device that is compact.

OBJECT OF THE INVENTION

An object of the invention is to propose a compact RF device that meets the isolation constraints set out above when use is being made of frequency bands that are adjacent.

SUMMARY OF THE INVENTION

In order to achieve this object, there is provided an RF device comprising:

a first antenna set made up of a first antenna and a second antenna, the first and second antennas being planar in shape and both lying in a common first plane, the first antenna being arranged to operate in a first frequency band and the second antenna being arranged to operate in a second frequency band;

a first isolator, the first isolator being planar in shape and lying in the first plane between the first and second antennas, the first isolator having at least one branch that is electrically conductive, the first isolator being electrically floating, the first isolator being arranged to reduce first coupling by electromagnetic radiation between the first and second antennas in the first frequency band and/or in the second frequency band.

The RF device of the invention is particularly advantageous, since the arrangement of the first and second antennas

2

together with the configuration of the first isolator that is not electrically connected to a ground plane between said antennas ensure that the RF device is compact while meeting the isolation constraints set out above.

5 In a particular embodiment, the first and second frequency bands are separated by a frequency gap lying in the range approximately 0 megahertz (MHz) to approximately 1 GHz.

In a particular embodiment, the first antenna set and the first isolator are positioned on a support made out of a dielectric material, the support lying in the first plane.

In a particular embodiment, the first isolator has first and second branches that are both electrically conductive, the second branch being substantially perpendicular to the first branch and projecting from a central portion of the first branch, a free end of the second branch being open circuit, the first isolator thus being T-shaped.

In a particular embodiment, the first and second antennas are planar dipole antennas, each being rectangular in shape, 20 the first antenna being arranged to generate a first maximum electric field along a first axis, the second antenna being arranged to generate a second maximum electric field along a second axis, and the first and second axes being substantially parallel to each other.

25 In a particular embodiment, the first and second axes are oriented at substantially 45° relative to the second branch.

In a particular embodiment, the first and second axes are substantially perpendicular to the second branch.

In a particular embodiment, the first maximum electric 30 field is greater than the second maximum electric field, one end of the first branch of the first isolator being spaced apart from the first axis by a distance lying in the range 5 millimeters (mm) to 1.5 centimeters (cm).

In a particular embodiment, the first isolator is arranged to 35 reduce the first coupling by electromagnetic radiation to a greater extent in the first frequency band, the first branch of the first isolator having a predefined length that is substantially equal to at least one quarter of a first wavelength λ_A , the first wavelength λ_A being such that:

$$\lambda_A = \frac{c}{v_1 \times \sqrt{\epsilon_r}}$$

45 where v_1 is a first center frequency centered between the maximum frequency and the minimum frequency of the first frequency band, and where ϵ_r is the dielectric permittivity of the medium in which the first isolator lies, the medium being a dielectric support or air.

In a particular embodiment, the first isolator is arranged to 50 reduce the first coupling by electromagnetic radiation in equal manner in the first and second frequency bands, the first branch of the first isolator having a predefined length that is substantially equal to at least one quarter of a first wavelength λ_A , the first wavelength λ_A being such that:

$$\lambda_A = \frac{c}{\frac{v_1 + v_2}{2} \times \sqrt{\epsilon_r}}$$

60 where v_1 is a first center frequency centered between the maximum frequency and the minimum frequency of the first frequency band, where v_2 is a second center frequency centered between the maximum frequency and the minimum frequency of the second frequency band, and where ϵ_r is the

dielectric permittivity of the medium in which the first isolator lies, the medium being a dielectric support or air.

In a particular embodiment, the second branch of the first isolator has a predefined length that is substantially equal to one quarter of the first wavelength λ_A .

In a particular embodiment, the first branch of the first isolator has a width that is predefined so that the characteristic impedance of said first branch is substantially equal to the characteristic impedance of one antenna selected from the first and second antennas, the second branch of the first isolator having a width that is predefined so that the characteristic impedance of said second branch is substantially equal to the characteristic impedance of the antenna selected from the first and second antennas.

In a particular embodiment, the first branch of the first isolator has a width that is predefined so that the characteristic impedance of said first branch lies substantially in the range 75 ohms (Ω) to 120 Ω , the second branch of the first isolator having a width that is predefined so that the characteristic impedance of said second branch lies substantially in the range 75 Ω to 120 Ω .

In a particular embodiment, the first isolator has three branches that are all electrically conductive and that are arranged in such a manner that said first isolator is Y-shaped.

In a particular embodiment, the above-described RF device further comprises at least one second isolator having at least one electrically conductive branch, the second isolator being electrically floating, the second isolator being positioned on one side of a particular antenna selected from the first and second antennas, said side of the particular antenna being remote from the first isolator, the second isolator being arranged to correct a modification to the directivity of the particular antenna as caused by the presence of the first isolator.

In a particular embodiment, the second isolator has a single electrically conductive branch, said isolator thus having a shape that is longitudinal.

In a particular embodiment, the above-described RF device has a third antenna extending in a second plane, the second isolator also being arranged to reduce second coupling by electromagnetic radiation between the third antenna and the particular antenna over a particular frequency band in which the particular antenna operates and over a third frequency band in which the third antenna operates.

In a particular embodiment, the second isolator is arranged to reduce the second coupling by electromagnetic radiation to a greater extent in the particular frequency band, the single branch of the second isolator having a predefined length that is substantially equal to half a second wavelength λ_B , the second wavelength λ_B being such that:

$$\lambda_B = \frac{c}{v_{\#} \times \sqrt{\epsilon_r}}$$

where $v_{\#}$ is a particular center frequency centered between the maximum frequency and the minimum frequency of the particular frequency band, and where ϵ_r is the dielectric permittivity of the medium in which the second isolator lies, the medium being a dielectric support or air.

In a particular embodiment, the second isolator is arranged to reduce the second coupling by electromagnetic radiation in equal manner in the particular frequency band and in the third frequency band, the single branch of the second isolator having a predefined length that is substan-

tially equal to half a second wavelength λ_B , the second wavelength λ_B being such that:

$$5 \quad \lambda_B = \frac{c}{\frac{v_{\#} + v_3}{2} \times \sqrt{\epsilon_r}}$$

where $v_{\#}$ is a particular center frequency centered between the maximum frequency and the minimum frequency of the particular frequency band, where v_3 is a third center frequency centered between the maximum frequency and the minimum frequency of the third frequency band, and where ϵ_r is the dielectric permittivity of the medium in which the second isolator lies, the medium being a dielectric support or air.

In a particular embodiment, the branch of the second isolator has a width that is predefined so that the characteristic impedance of said branch is substantially equal to the characteristic impedance of an antenna selected from the particular antenna and the third antenna.

In a particular embodiment, the branch of the first isolator has a width that is predefined so that the characteristic impedance of said branch lies substantially in the range 75 Ω to 120 Ω .

In a particular embodiment, the second isolator is situated in the proximity of an intersection between the first and second planes.

In a particular embodiment, the second isolator is positioned in an intersecting plane that intersects the first and second planes.

In a particular embodiment, the second isolator forms a rounded corner between the first and second planes.

In a particular embodiment, the first and second planes are perpendicular.

In a particular embodiment, the above-described RF device includes a second antenna set comprising the third antenna and a fourth antenna, the second antenna set being similar to the first antenna set, and also including a third isolator similar to the first isolator and positioned between the third and fourth antennas.

In a particular embodiment, the above-described RF device comprises a support having four faces comprising two mutually parallel first faces and two mutually parallel second faces, two first antenna sets each positioned on a distinct first face, and two second antenna sets each positioned on a distinct second face, the RF device further comprising two first isolators each positioned between the first and second antennas of a distinct first antenna set, two third isolators each positioned between a third antenna and a fourth antenna of a distinct second antenna set, and four second isolators each positioned in a distinct corner of the support.

The invention also provides a MIMO system comprising an RF device as described above together with an RF transmitter and an RF receiver both connected to the first and second antenna sets of said RF device.

The invention also provides electronic equipment comprising a MIMO system as described above.

In a particular embodiment, the electronic equipment is a residential gateway.

Other characteristics and advantages of the invention appear on reading the following description of particular, nonlimiting embodiments of the invention.

BRIEF DESCRIPTION OF THE DRAWINGS

The description of embodiments refers to the accompanying drawings, in which:

FIG. 1 is a plan view of an RF device in an embodiment; FIG. 2 shows a simulation of the operation of the RF device shown in FIG. 1 when the first antenna is transmitting, and the first isolator is not present;

FIG. 3 shows a simulation of the operation of the RF device shown in FIG. 1 when the first antenna is transmitting, and the first isolator is present;

FIG. 4 shows a simulation of the operation of the RF device shown in FIG. 1 when the second antenna is transmitting, and the first isolator is not present;

FIG. 5 shows a simulation of the operation of the RF device shown in FIG. 1 when the second antenna is transmitting, and the first isolator is present;

FIG. 6 plots the parameter S_{21} as a function of the frequency of the RF device shown in FIG. 1;

FIG. 7 plots the radiation patterns of the first antenna of the RF device shown in FIG. 1;

FIG. 8 plots the radiation patterns of the second antenna of the RF device shown in FIG. 1;

FIG. 9 is a perspective view of a first variant of the RF device in an embodiment;

FIG. 10A shows a first position of the second isolator of the RF device shown in FIG. 9;

FIG. 10B shows a second position of the second isolator of the RF device shown in FIG. 9;

FIG. 11 shows a simulation in a first plane of the electric field of the RF device shown in FIG. 9 when the first antenna is transmitting, and the first isolator is not present;

FIG. 12 shows a simulation in a first plane of the electric field of the RF device shown in FIG. 9 when the first antenna is transmitting, and the first isolator is present;

FIG. 13 shows a simulation in a second plane of the electric field of the RF device shown in FIG. 9 when the first antenna is transmitting, and the first isolator is not present;

FIG. 14 shows a simulation in a second plane of the electric field of the RF device shown in FIG. 9 when the first antenna is transmitting, and the first isolator is present;

FIG. 15 plots the parameter S_{21} as a function of frequency for the RF device shown in FIG. 9;

FIG. 16 plots the radiation patterns of the first antenna of the RF device shown in FIG. 9;

FIG. 17 plots the radiation patterns of the third antenna of the RF device shown in FIG. 9;

FIG. 18 is a perspective view of a third variant of the RF device in an embodiment;

FIG. 19 is a simulation of the electric field of the RF device shown in FIG. 18 when the first antenna is transmitting, and the isolator device is not present;

FIG. 20 is a simulation of the electric field of the RF device shown in FIG. 18 when the second antenna is transmitting, and the isolator device is not present;

FIG. 21 is a simulation of the electric field of the RF device shown in FIG. 18 when the first antenna is transmitting, and the isolator device is present;

FIG. 22 is a simulation of the electric field of the RF device shown in FIG. 18 when the second antenna is transmitting, and the isolator device is present;

FIG. 23 plots the combined gain radiation patterns of the first antenna group of the RF device shown in FIG. 18;

FIG. 24 plots the combined gain radiation patterns of the second antenna group of the RF device shown in FIG. 18;

FIG. 25 is a block diagram of a piece of electronic equipment incorporating a MIMO system including the RF device shown in FIG. 18;

FIG. 26 shows a residential gateway incorporating the RF device shown in FIG. 18.

DETAILED DESCRIPTION OF THE INVENTION

With reference to FIG. 1, there follows a description of an RF device 1 in an embodiment.

The RF device 1 includes a first antenna set 2 comprising a first antenna 2a and a second antenna 2b. The first and second antennas 2a and 2b are planar shapes and both of them lie in a first plane 3. The first plane 3 is defined by an axis X and by an axis Z, the axes X and Z being perpendicular.

In this example, the first and second antennas 2a and 2b are positioned on a support 4 made out of a dielectric material and lying in the first plane 3. Specifically, in this example, the support 4 is made out of a plastics material presenting dielectric permittivity greater than 1 (e.g. the dielectric permittivity of the plastics material used is equal to about 3).

The first antenna 2a operates in a first frequency band, and the second antenna 2b operates in a second frequency band. It should be understood that when an antenna is said herein to operate in a frequency band (or at a frequency), that means that said antenna is designed to transmit and/or receive RF signals optimally in said frequency band (or at said frequency).

Also, in this example, the first and second frequency bands are different, but adjacent. When the first and second frequency bands are said herein to be "adjacent", that means that they are separated by a frequency gap lying in the range approximately 0 MHz to approximately 1 GHz. For example, if the first frequency band is lower than the second frequency band, said frequency gap is the difference between the minimum frequency of the second frequency band and the maximum frequency of the first frequency band.

By way of example, the first antenna 2a could be a dual-band antenna operating at a frequency equal to 2.4 GHz and at a frequency equal to 5 GHz, and the second antenna 2b could be a simple single-band antenna operating at a frequency of 6 GHz.

By way of another example, the first antenna 2a could be a single-band antenna operating in a 5 GHz frequency band in the range 5170 MHz to 5835 MHz, and the second antenna 2b could be a single-band antenna operating in a 6 GHz frequency band in the range 5925 MHz to 7125 MHz.

In this example, the first and second antennas 2a and 2b are planar dipole antennas on supports that are rectangular in shape. The first and second antennas 2a and 2b both present respective omnidirectional radiation patterns that are toroidal in shape. The first antenna 2a generates a first maximum electric field on a first axis E_{2a} and the second antenna 2b generates a second maximum electric field on a second axis E_{2b} . The first axis E_{2a} is an axis of symmetry of the first antenna 2a parallel to its width. The second axis E_{2b} is an axis of symmetry of the second antenna 2b parallel to its width.

In this example, the first and second axes E_{2a} and E_{2b} are parallel.

The RF device 1 also has a first isolator 5 of planar shape that lies in the first plane 3 between the first and second antennas 2a and 2b. In this example, the first isolator 5 is generally centered between the first and second antennas 2a and 2b.

The first isolator 5 is positioned on the support 4 and it is fastened by fastener means, e.g. comprising thermoplastic stakes, adhesive, or indeed screws.

Still with reference to FIG. 1, the first isolator 5 comprises both a first branch 6 and a second branch 7. In this example, the first and second branches 6 and 7 of the first isolator 5 are formed by plane, rectilinear tracks made out of a conductive material, e.g. aluminum, copper, or indeed iron.

Also, in this example the second branch 7 of the first isolator 5 is perpendicular to the first branch 6 of the first isolator 5 and it projects from a central portion of said first branch 6. The first isolator 5 is thus T-shaped. The T-shape is simple and it facilitates fabrication of the first isolator 5, since it is a shape that can be cut out accurately (in particular from a metal plate) and that is easily reproducible.

Thus, the first branch 6 of the first isolator 5 is an open circuit transmission line between a first end 6a and a second end 6b. Furthermore, the second branch 7 of the first isolator 5 is a stub that is open circuit at a free end 7a. Thus, the first and second branches 7 and 6 of the first isolator 5 are electrically connected together in parallel. The first isolator 5 is thus a passive element that performs the function of a reciprocal bandstop resonator. The first isolator 5 thus presents a transmission coefficient that is the same regardless of the flow direction of electric current flowing through its first branch 6 and its second branch 7.

Also, the first isolator 5 is not electrically connected. In particular, the first isolator 5 is not connected to an electrical ground plane. The first isolator 5 is thus electrically floating. It should be observed in particular that this floating configuration of the first isolator 5 is particularly different from the solutions of the prior art. Specifically, in the prior art, there exist isolators that are mounted on a printed circuit board (PCB), but using a PCB (which presents, in particular, magnetic permeability) requires said isolators to be connected to the electrical ground plane of said PCB.

In this example, the first and second axes E_{2a} and E_{2b} are both oriented at an angle equal to 45° relative to the second branch 7 of the first isolator 5. The first axis E_{2a} passes directly in the vicinity of the first end 6a of the first branch 6 of the first isolator 5.

The dimensions of the first isolator 5 are predefined as a function of the available space, of the environment in which it is used, and of the frequency band in which it is to have maximum influence. Specifically, it is important to consider the environment in which the device 1 in an embodiment of the invention is to be applied, and in particular the electrical parameters of the materials used (such as dielectric permittivity), which have an impact on the wavelengths, on the resonant frequencies, and also on the characteristic impedances of the transmission lines (i.e. of the tracks).

Preferably, the first branch 6 of the first isolator 5 has a length that is approximately equal to at least one quarter of a first wavelength λ_A taking account of the medium in which the first isolator 5 extends.

In a first example, the first isolator 5 is designed to attenuate coupling by electromagnetic radiation between the first and second antennas 2a and 2b in the first frequency band and also in the second frequency band, but to do so to a greater extent in the first frequency band (in which the first antenna 2a operates). If the medium in which the first isolator 5 extends is air, then the first wavelength λ_A is calculated using dielectric permittivity equal to 1. In contrast, if the medium in which the first isolator 5 extends is a dielectric support (e.g. a support made of plastics material), then the dielectric permittivity of said dielectric support is taken into account and the first wavelength λ_A is such that:

$$\lambda_A = \frac{c}{v_1 \times \sqrt{\epsilon_r}}$$

where ϵ_r is the dielectric permittivity of the material used for making the dielectric support, where v_1 is a first center frequency that is centered between the maximum frequency and the minimum frequency of the first frequency band (in which the first antenna 2a operates), and where c is the velocity of the electromagnetic wave.

For example, if the first frequency band is a frequency band in the range 5.1 GHz to 5.9 GHz, then the first center frequency v_1 is equal to about 5.5 GHz.

In another example, the first isolator 5 is designed to attenuate the coupling by electromagnetic radiation between the first and second antennas 2a and 2b in balanced (or equal) manner between the first and second frequency bands. By way of example, the first frequency band is a so-called "5 GHz" frequency band and the second frequency band is a so-called "6 GHz" frequency band. If the medium in which the first isolator 5 extends is not air, then the first wavelength λ_A is such that:

$$\lambda_A = \frac{c}{\frac{v_1 + v_2}{2} \times \sqrt{\epsilon_r}}$$

where v_1 is the first center frequency of the first frequency band (e.g. 5.5 GHz), and where v_2 is a second center frequency that is centered between the maximum frequency and the minimum frequency of the second frequency band (e.g. 6.5 GHz). Other examples of dimensions for the first branch 6 of the first isolator 5 may be obtained depending on the isolation desired for the first frequency band or for the second frequency band.

The second branch 7 of the first isolator 5 has a length that is approximately equal to one quarter of the selected first wavelength λ_A . The selected first wavelength λ_A corresponds to a selected first frequency that, by way of example, is equal to 6.2 GHz when it is desired to obtain isolation at the beginning of the so-called 6 GHz frequency band (UNII-5). By way of example, the selected first frequency may equally well depend both on the first center frequency v_1 of the first frequency band (in which the first antenna 2a operates) and also on the second center frequency v_2 of the second frequency band (in which the second antenna 2b operates). For example, the selected center frequency may be equal to $(v_1 + v_2)/2$.

In an example, the dimensions of the first isolator 5, and in particular the respective widths of the first branch 6 and of the second branch 7, depend on the characteristics of a selected one of the first and second antennas 2a and 2b. The respective dimensions of the first and second antennas 2a and 2b are considered in order to select the greatest dimension(s). For example, when the first frequency band (in which the first antenna 2a operates) is the so-called 5 GHz frequency band and the second frequency band (in which the second antenna 2b operates) is the so-called 6 GHz frequency band, then the radiating tracks or strands of the first antenna 2a are of dimensions or sizes that are greater than the radiating tracks or strands of the second antenna 2b. The widths of the radiating tracks or strands of the selected antenna serve to determine the width of the first branch 6 and/or of the second branch 7 of the first isolator 5. If the first frequency band (first antenna 2a) is the so-called 5 GHz

frequency band and the second frequency band (second antenna **2b**) is the so-called 6 GHz frequency band, then the respective widths of the first and second branches **6** and **7** of the first isolator **5** may be about 2.5 mm to 3 mm.

The first antenna **2a** is selected so as to determine the dimensions of the first isolator **5** and the first antenna **2a** is positioned on a PCB, itself resting on a first dielectric support (e.g. made out of a plastics material), with the assembly (the PCB and the first plastics material) presenting dielectric permittivity that is equal to about 4.3. In an example, the first isolator **5** is positioned on a second dielectric support (e.g. made out of a plastics material) that may be identical to or different from the first dielectric support on which the first antenna **2a** is positioned, and that presents dielectric permittivity equal to about 3. As a result of the proximity of two different dielectric permittivities, and given that the first antenna **2a** is selected for determining the dimensions of the first isolator **5**, the respective characteristic impedances of the first and second branches **6** and **7** of the first isolator **5** are approximately equal to the characteristic impedance of the first antenna **2a**.

In other examples, the first and second branches **6** and **7** of the first isolator **5** are of respective widths that ensure that the respective characteristic impedances of said first and second branches **6** and **7** lie in the range [75Ω, 120Ω]. This makes it possible to maximize electric current flowing through said first and second branches **6** and **7** and also to maximize the attenuation of coupling by electromagnetic radiation.

Also, the first isolator **5** operates in the near field. Still assuming that the first isolator **5** is arranged to attenuate coupling by electromagnetic radiation between the first and second antennas **2a** and **2b** more strongly in the first frequency band, then the distance between the first end **6a** of the first branch **6** of the first isolator **5** and the first axis E_{2a} lies in the range 5 mm to 1 cm. This distance serves to optimize limiting of the magnitude of the electric field generated by the first antenna **2a** and picked up by the second antenna **2b**. In another example, this distance is greater than 1 cm, e.g. 1.5 cm.

FIGS. 2, 3, 4, and 5 illustrate the role of the first isolator **5** in the RF device 1. In this example, the first antenna **2a** is a Wi-Fi antenna operating in a frequency band ranging from 5.1 GHz to 5.9 GHz. In this example, the second antenna **2b** is a Wi-Fi antenna operating in a frequency band ranging from 5.9 GHz to 7.2 GHz. The first frequency band of the first antenna **2a** and the second frequency band of the second antenna **2b** are thus adjacent.

In each of FIGS. 2, 3, 4, and 5, curved field lines represent the orientation of the electric field in the first plane **3**. Furthermore, in this example, the magnitude of said electric field (in volts per meter ($V \cdot m^{-1}$)) is represented by grayscale levels.

With reference to FIGS. 2 and 3, the first antenna **2a** is operating in transmission, i.e. it is transmitting RF signals in its frequency band. Field lines **8** thus represent the orientation of the electric field generated by the first antenna **2a**. In contrast, the second antenna **2b** is inactive, i.e. it is neither transmitting nor receiving any RF signals in its frequency band.

When the RF device 1 does not include the first isolator **5** (FIG. 2), the electric field generated by the first antenna **2a** propagates without obstacle through the support **4** to the second antenna **2b**. The second antenna **2b** thus picks up a large portion of the electric field generated by the first antenna **2a**. The field lines **8** are thus concentrated on and in the neighborhood of the second antenna **2b**. Thus, knowing

that the first and second antennas **2a** and **2b** operate in respective frequency bands that are adjacent, coupling by electromagnetic radiation between the first and second antennas **2a** and **2b** is considerable.

When the radiofrequency device 1 includes the first isolator **5** (FIG. 3), the electric field generated by the first antenna **2a** is filtered, i.e. it is attenuated because of the reciprocal bandstop resonator function of said first isolator **5**. The field lines **8** are thus concentrated on and in the neighborhood of the first isolator **5** (and not in the neighborhood of the second antenna **2b**). More precisely, the electric field generated by the first antenna **2a** is concentrated at the first end **6a** of the first branch **6** of the first isolator **5** and at the free end **7a** of the second branch **7** of the first isolator **5**. Coupling by electromagnetic radiation between the first and second antennas **2a** and **2b** is thus significantly reduced. Also, the first isolator **5** modifies the near field orientation of the electric field generated by the first antenna **2a**.

In the example shown in FIGS. 4 and 5, the first antenna **2a** is inactive and the second antenna **2b** is operating in transmission. Field lines **9** thus represent the orientation of the electric field generated by the second antenna **2b**.

When the RF device 1 does not include the first isolator **5** (FIG. 4), the electric field generated by the second antenna **2b** propagates without obstacle through the support **4** to the first antenna **2a**. The field lines **9** are thus concentrated on and in the neighborhood of the first antenna **2a**.

Coupling by electromagnetic radiation between the first and second antennas **2a** and **2b** is thus considerable.

When the RF device 1 includes the first isolator **5** (FIG. 5), the field lines **9** are concentrated at the first and second ends **6a** and **6b** of the first branch **6** of the first isolator **5** and at the free end **7a** of the second branch **7** of the first isolator **5**. The number of field lines **9** in the neighborhood of the first antenna **2a** is thus greatly reduced. Coupling by electromagnetic radiation between the first and second antennas **2a** and **2b** is thus significantly reduced.

It should be observed that the first isolator **5** presents better performance when it is the first antenna **2a** that is transmitting (in comparison with when it is the second antenna **2b** that is transmitting). This result is logical, since the dimensions of the first isolator **5** in this example are determined to operate in the neighborhood of the maximum frequency of the first frequency band (ranging from 5.1 GHz to 5.9 GHz).

FIG. 6 plots the amplitude in dB of a parameter S_{21} (known as the “scattering” parameter) as a function of frequency. The parameter S_{21} corresponds to the transmission coefficient between the second antenna **2b** and the first antenna **2a**. The curve **10** is the curve for the parameter S_{21} when the first isolator **5** is not present, and the curve **11** is the curve for the parameter S_{21} when the first isolator **5** is present. In this example, the first isolator **5** has dimensions designed to attenuate coupling by electromagnetic radiation between the first and second antennas **2a** and **2b** in a frequency band ranging from 5 GHz to 7 GHz. It can clearly be seen that the first isolator **5** reduces the amplitude of the parameter S_{21} in the frequency band for which it is designed. Specifically, in the vicinity of a frequency equal to 5.5 GHz, there can be seen minimum reduction in the amplitude of the parameter S_{21} that is equal to about 5 decibels (dB) (reference R1 in FIG. 6), and in the vicinity of a frequency equal to 6.3 GHz, there can be seen maximum reduction of about 34 dB (reference R2 in FIG. 6). The first isolator **5** thus serves effectively to attenuate coupling by electromagnetic

11

radiation between the first and second antennas **2a** and **2b** in the frequency band for which it is designed.

With reference to FIGS. 7 and 8, an axis Y has been added that is perpendicular to the axes X and Z such that the three axes X, Y, and Z form an orthogonal reference frame (in three-dimensional space), with each of these figures showing three sections, a first section XZ (i.e. a section on the first plane 3), a second section YZ, and a third section XY.

FIG. 7 plots a radiation pattern 12 for the first antenna **2a** in the first section XZ, a radiation pattern 13 for the first antenna **2a** in the second section YZ, and a radiation pattern 14 for the first antenna **2a** in the third section XY. The radiation patterns 12, 13, and 14 correspond to the situation as shown in FIGS. 2 and 3, i.e. the first antenna **2a** is transmitting (in the first frequency band ranging from 5.1 GHz to 5.9 GHz), and the second antenna **2b** is inactive. It is common practice to characterize an RF antenna by using its radiation pattern, which plots the angular distribution (in degrees) of the gain of said antenna (in decibels relative to isotropic (dB)).

In the radiation patterns 12, 13, and 14, the continuous line curve corresponds to the far field directivity of the first antenna **2a** when the first isolator 5 is not present, and the dashed line curve corresponds to the far field directivity of the first antenna **2a** when the first isolator 5 is present.

The radiation patterns 12, 13, and 14 reveal that the first isolator 5 modifies the far field directivity of the first antenna **2a**.

In particular, the radiation pattern 12 in the first section XZ shows that the far field directivity of the first antenna **2a** is more uniform when the first isolator 5 is present (curve 12b). The term "uniform" is used to mean that the gain of the first antenna **2a** is substantially constant as a function of the propagation angle of the radiation transmitted by said first antenna **2a**. More precisely, when the first isolator 5 is not present (curve 12a), the maximum relative variation in the gain of the first antenna **2a** is about 8 dB, whereas when the first isolator 5 is present (curve 12b), the maximum relative variation in the gain of the first antenna **2a** is about 3 dB.

The radiation pattern 13 in the second section YZ does not show any significant shift in the far field directivity of the first antenna **2a**.

The radiation pattern 14 in the third section XY shows that the maximum of the gain of the first antenna is shifted when the first isolator 5 is present. Specifically, when the first isolator 5 is not present (curve 14a), the gain of the first antenna **2a** is at a maximum in the vicinity of an angle of 270°, whereas when the first isolator 5 is present (curve 14b), the gain of the first antenna **2a** is at a maximum in the vicinity of an angle of 180°.

FIG. 8 plots a radiation pattern 15 for the second antenna **2b** in the first section XZ, a radiation pattern 16 for the second antenna **2b** in the second section YZ, and a radiation pattern 17 for the second antenna **2b** in the third section XY. The radiation patterns 15, 16, and 17 correspond to the situation as shown in FIGS. 4 and 5, i.e. the first antenna **2a** is inactive and the second antenna **2b** is transmitting (in the second frequency band ranging from 5.9 GHz to 7.2 GHz).

In the radiation patterns 15, 16, and 17, the continuous line curve corresponds to the far field directivity of the second antenna **2b** when the first isolator 5 is not present, and the dashed line curve corresponds to the far field directivity of the second antenna **2b** when the first isolator 5 is present.

The radiation patterns 15, 16, and 17 reveal that the influence of the first isolator 5 on the far field directivity of the second antenna **2b** is moderate. Specifically, the profile

12

of the far field directivity of the second antenna **2b** when the first isolator 5 is not present is generally similar to the profile of the far field directivity of the second antenna **2b** when the first isolator 5 is present. This is due to the fact that the second axis E_{2b} of the second maximum electric field of the second antenna **2b** does not lie directly in the vicinity of the first isolator 5.

It should be observed that the dimensions of the first isolator 5 can be adjusted depending on the intended frequency band.

It should be observed that the greater the conductivity of the material used for making the first isolator 5, the greater the isolation performance of said first isolator 5.

Also, the first axis E_{2a} of the first maximum electric field (of the first antenna **2a**) and the second axis E_{2b} of the second maximum electric field (of the second antenna **2b**) could be perpendicular to the second branch 7 of the first isolator 5.

With reference to FIG. 9, the RF device 1 in an embodiment further includes at least one second isolator 18. The RF device 1 could also include only one second isolator 18.

The second isolator 18 is positioned on one side of a particular one of the first and second antennas **2a** and **2b**, 25 which side of the particular antenna is remote from the first isolator. In FIG. 9, the particular antenna is the first antenna **2a**, which in this example is positioned to the left of the antenna **2b** (not shown in FIG. 9). The second isolator 18 is used to modify and to redirect the far field directivity of the first antenna **2a** resulting from the presence of the first isolator 5. The second isolator 18 is considered as an interfering element having an influence on the mapping of the electric field on a support 54.

In this example, the first antenna **2a** is positioned on the support 54 having a first face extending in the first plane 3 and a second face extending in a second plane 21. The second plane 21 is defined by the axes Y and Z. The second plane is thus oriented at an angle Ω equal to 90° relative to the first plane 3. It should be observed that the angle of inclination Q between the first plane 3 and the second plane 21 could be other than 90°.

In this example, the second isolator 18 is positioned in a corner of the support 54 defined by the intersection of the first and second planes 3 and 21, and it is fastened by 45 fastener means, e.g. comprising stakes, adhesive, or indeed screws.

In this example, the second isolator 18 has a single branch 19. In this example, the branch 19 of the second isolator 18 is formed by a rectilinear plane track made out of a conductive material, e.g. aluminum, copper, or indeed iron. The second isolator 18 is thus of elongate I-shape. The I-shape is simple and it facilitates fabrication of the second isolator 18 since it is a shape that can be cut out accurately (in particular from a metal plate) and that is easily reproducible.

Thus, the branch 19 of the second isolator 18 is an open circuit transmission line between an end 19a and an end 19b. The second isolator is thus an element that is passive.

Also, the second isolator 18 is not electrically connected. In particular, the second isolator 18 is not connected to an electrical ground plane. The second isolator 18 is thus electrically floating.

Still with reference to FIG. 9, provision may be made for the RF device 1 also to have a third antenna **20b**. The third antenna **20b** is planar in shape, and in this example, it lies in the second plane 21.

The third antenna **20b** operates in a third frequency band. The third frequency band could be different from the first

and second, but it could equally well be similar to the first frequency band or to the second frequency band.

By way of example, the third antenna **20b** could be a single-band antenna operating in the so-called 6 GHz frequency band.

In this example, the third antenna **20b** is a planar dipole antenna of rectangular shape. Thus, the third antenna **20b** presents an omnidirectional radiation pattern in the shape of a torus. The third antenna **20b** generates a third maximum electric field along a third axis E_{20b} . The position of the third antenna **20b** in the second plane **21** is thus defined along the third axis E_{20b} .

In this example, and with reference to FIG. 9, the second isolator **18** is positioned in a corner of the support **54** between the third antenna **20b** and an antenna that is the first antenna **2a**.

With reference to FIG. 10A, the second isolator **18** may be positioned in an intersecting plane **22** that intersects the first and second planes **3** and **21**. The second isolator **18** is thus positioned at least in part on a chamfer of the support **54**.

With reference to FIG. 10B, the second isolator **18** may equally well form a rounded corner **23** between the first and second planes **3** and **21**. The second isolator **18** is thus positioned at least in part on a fillet of the support **54**.

When it is placed between the first and third antennas **2a** and **20b**, the second isolator **18** serves to reduce coupling by electromagnetic radiation between said first and third antennas **2a** and **20b**.

The dimensions of the second isolator **18** are predefined as a function of the available space, of the environment in which it is used, and of the frequency band in which it is to have maximum influence.

The dimensions of the second isolator **18** are given herein for the situation in which the second isolator **18** is arranged to isolate the third antenna **20b** from the electric field generated by the first antenna **2a**.

Preferably, the branch **19** of the second isolator **18** has a length that is approximately equal to at least one half of a second wavelength λ_B taking account of the medium in which the second isolator **18** extends.

In a first example, the second isolator **18** is designed to attenuate the coupling by electromagnetic radiation between the first and third antennas **2a** and **20b** both in the first frequency band (in which the first antenna **2a** operates), and also in the third frequency band (in which the third antenna **20b** operates), but to a lesser extent than in the first frequency band. If the medium in which the second isolator **18** extends is air, then the second wavelength λ_B is calculated using dielectric permittivity equal to 1. In contrast, if the medium in which the second isolator **18** extends is a dielectric support (e.g. a support made of plastics material), then the dielectric permittivity of said dielectric support is taken into account and the second wavelength λ_B is such that:

$$\lambda_B = \frac{c}{v_g \times \sqrt{\epsilon_r}}$$

where ϵ_r is the dielectric permittivity of the material used for making the dielectric support, where c is the velocity of the electromagnetic wave, and where v_g is the first center frequency of the first frequency band (in which the first antenna **2a** operates).

In another example, the second isolator **18** is designed to attenuate the coupling by electromagnetic radiation between

the first and third antennas **2a** and **20b** in balanced (or equal) manner between the first frequency band and the third frequency band. By way of example, the first frequency band is the so-called 5 GHz frequency band and the third frequency band is the so-called 6 GHz frequency band. If the medium in which the second isolator **18** extends is not air, then the second wavelength λ_B is such that:

$$\lambda_B = \frac{c}{\frac{v_g + v_3}{2} \times \sqrt{\epsilon_r}}$$

where v_g use the first center frequency of the first frequency band (e.g. 5.5 GHz), and where v_3 is a third center frequency that is centered between the maximum frequency and the minimum frequency of the third frequency band (e.g. 6.5 GHz). Other examples of dimensions for the branch **19** of the second isolator **18** may be obtained depending on the isolation desired for the first frequency band or for the third frequency band.

In an example, the dimensions of the second isolator **18**, and in particular the width of the branch **19**, depend on the characteristics of a selected one of the first and third antennas **2a** and **20b**. The respective dimensions of the first and third antennas **2a** and **20b** are considered in order to select the greatest dimension(s). For example, when the first frequency band (in which the first antenna **2a** operates) is the so-called 5 GHz frequency band and the third frequency band (in which the third antenna **20b** operates) is the so-called 6 GHz frequency band, then the radiating tracks or strands of the first antenna **2a** are of dimensions or sizes that are greater than the radiating tracks or strands of the third antenna **20b**. The widths of the radiating tracks or strands of the selected antenna (from among the first and third antennas **2a** and **20b**) serve to determine the width of the branch **19** of the second isolator **18**. If the first frequency band (first antenna **2a**) is the so-called 5 GHz frequency band and the third frequency band (third antenna **20b**) is the so-called 6 GHz frequency band, then the widths of the branch **19** of the second isolator **18** may be about 2.5 mm to 3 mm.

The first antenna **2a** is selected so as to determine the dimensions of the second isolator **18** and the first antenna **2a** is positioned on a PCB, itself resting on a first dielectric support (e.g. made out of a plastics material), with the assembly (the PCB and the first plastics material) presenting dielectric permittivity that is equal to about 4.3. In an example, the second isolator **18** is positioned on a second dielectric support (e.g. made out of a plastics material) that may be identical to or different from the first dielectric support on which the first antenna **2a** is positioned, and that presents dielectric permittivity equal to about 3. As a result of the proximity of two different dielectric permittivities, and given that the first antenna **2a** is selected for determining the dimensions of the second isolator **18**, the characteristic impedance of the branch **19** of the second isolator **18** is approximately equal to the characteristic impedance of the first antenna **2a**.

In other examples, the branch **19** of the second isolator **18** is of a width that ensures that the characteristic impedance of said branch **19** lies in the range [75Ω, 120Ω]. This makes it possible to maximize electric current flowing through said branch **19** and also to maximize the attenuation of coupling by electromagnetic radiation.

In another example, the width of the branch **19** of the second isolator **18** is not less than the width of the first branch **6** and/or of the second branch **7** of the first isolator

5. In yet another example, the width of the branch **19** of the second isolator **18** is approximately twice the width of the first branch **6** and/or of the second branch **7** of the first isolator **5**.

Also, the second isolator **18** operates in the near field. Still assuming in this example that the second isolator **18** is arranged to isolate the third antenna **20b** from the electric field generated by the first antenna **2a**, then the distance between the second isolator **18** and the first axis E_{2a} lies in the range 5 mm to 1 cm. This distance serves to optimize limiting of the magnitude of the electric field generated by the first antenna **2a** and picked up by the third antenna **20b**. In another example, this distance is greater than 1 cm, e.g. 1.5 cm.

FIGS. **11**, **12**, **13**, and **14** illustrate the role of the second isolator **18** in the RF device **1**. In this example, the first antenna **2a** is a Wi-Fi antenna operating in a frequency band ranging from 5.1 GHz to 5.9 GHz, i.e. in the so-called 5 GHz frequency band. In this example, the third antenna **20b** is a Wi-Fi antenna operating in a frequency band ranging from 5.9 GHz to 7.2 GHz, i.e. in the so-called 6 GHz frequency band. The first frequency band of the first antenna **2a** and the third frequency band of the third antenna **20b** are thus adjacent.

In each of FIGS. **11**, **12**, **13**, and **14**, curved field lines **24** represent the orientation of the electric field in the first plane **3** and in the second plane **21**. Furthermore, in this example, the magnitude of said electric field (in $V \cdot m^{-1}$) is represented by grayscale levels. In this example, the first antenna **2a** is operating in transmission and the third antenna **20b** is inactive.

FIGS. **11** and **12** show the orientation and the magnitude of the electric field generated by the first antenna **2a** in the first plane **3**.

FIGS. **13** and **14** show the orientation and the magnitude of the electric field generated by the first antenna **2a** in the second plane **21**.

When the RF device **1** does not include the second isolator **18**, the electric field generated by the first antenna **2a** propagates through the support **54** along the first axis E_{2a} (FIG. **11**). Furthermore, the field lines **24** are concentrated at the third antenna **20b**, which shows that said third antenna **20b** picks up a significant portion of the electric field generated by the first antenna **2a** (FIG. **13**).

When the RF device **1** includes the second isolator **18** (FIGS. **12** and **14**), the electric field generated by the first antenna **2a** does not propagate along the first axis E_{2a} . The field lines **24** are thus concentrated at the ends **19a** and **19b** of the branch **19** of the second isolator **18**. In other words, the field lines **24** are deflected from their initial orientation (i.e. their orientation when the second isolator **18** is not present). Deflecting the field lines **24** serves also to attenuate the portion of the electric field generated by the first antenna **2a** and picked up by the third antenna **20b**. The second isolator **18** thus serves to reduce the coupling by electromagnetic radiation between the first and third antennas **2a** and **20b**.

FIG. **15** plots the amplitude in decibels of the parameter S_{21} as a function of frequency. The parameter S_{21} corresponds to the transmission coefficient between the third and first antennas **20b** and **2a**. The curve **25** is the curve for the parameter S_{21} when the second isolator **18** is not present, and the curve **26** is the curve for the parameter S_{21} when the second isolator **18** is present. In this example, the second isolator **18** has dimensions designed to attenuate coupling by electromagnetic radiation between the first and third antennas **2a** and **20b** in a frequency band ranging from 5 GHz to

7 GHz. The second isolator **18** reduces the amplitude of the amplitude of the parameter S_{21} a little in the frequency band for which it is designed. Specifically, and in the vicinity of a frequency equal to 5.2 GHz, there can be seen maximum reduction of about 8 dB (reference **R3** in FIG. **15**). The second isolator **18** thus serves to attenuate coupling by electromagnetic radiation a little between the first and third antennas **2a** and **20b** in the frequency band for which it is designed.

FIG. **16** plots a radiation pattern **27** for the first antenna **2a** in the first section **XZ**, a radiation pattern **28** for the first antenna **2a** in the second section **YZ**, and a radiation pattern **29** for the first antenna **2a** in the third section **XY**. The radiation patterns **27**, **28**, and **29** correspond to the situation is shown in FIGS. **11**, **12**, **13**, and **14**, i.e. the first antenna **2a** is transmitting (in the first frequency band ranging from 5.1 GHz to 5.9 GHz), and the third antenna **20b** is inactive.

In the radiation patterns **27**, **28**, and **29**, the continuous line curve corresponds to the far field directivity of the first antenna **2a** when the second isolator **18** is not present, and the dashed line curve corresponds to the far field directivity of the first antenna **2a** when the second isolator **18** is present.

The radiation patterns **27**, **28**, and **29** reveal that the second isolator **18** modifies the far field directivity of the first antenna **2a**.

In particular, the radiation pattern **27** in the first section **XZ** shows that the far field directivity of the first antenna **2a** is generally more uniform when the second isolator **18** is present (curve **27b**). More precisely, when the second isolator **18** is not present (curve **27a**), the maximum relative variation in the gain of the first antenna **2a** is about 7 dBi, whereas when the second isolator **18** is present (curve **27b**), the maximum relative variation in the gain of the first antenna **2a** is about 5 dBi.

The radiation pattern **28** in the third section **XY** shows that the maximum of the gain of the first antenna **2a** is shifted when the second isolator **18** is present. Specifically, when the second isolator **18** is not present (curve **28a**), the gain of the first antenna **2a** is at a maximum in angles over the range 210° to 300°, whereas when the second isolator **18** is present (curve **28b**), the gain of the first antenna **2a** is at a maximum in the vicinity of a first angle equal to 0° and in the vicinity of a second angle equal to 180°.

FIG. **17** plots a radiation pattern **30** for the third antenna **20b** in the first section **XZ**, a radiation pattern **31** for the third antenna **20b** in the second section **YZ**, and a radiation pattern **32** for the third antenna **20b** in the third section **XY**. The radiation patterns **30**, **31**, and **32** correspond to the situation in which the third antenna **20b** is transmitting (in the third frequency band ranging from 5.9 GHz to 7.2 GHz).

In the radiation patterns **30**, **31**, and **32**, the continuous line curve corresponds to the far field directivity of the third antenna **20b** when the second isolator **18** is not present, and the dashed line curve corresponds to the far field directivity of the third antenna **20b** when the second isolator **18** is present.

The radiation patterns **30**, **31**, and **32** reveal that the second isolator **18** has influence on the far field directivity of the third antenna **20b** that is almost negligible. Specifically, the profiles of the far field directivity and the gain values for the third antenna **20b** when the second isolator **18** is not present and when the second isolator **18** is present are substantially similar. This is due to the fact that the third axis E_{20b} of the third maximum electric field of the third antenna **20b** does not lie directly in the vicinity of the second isolator **18**.

It should be observed that the attenuation produced by the second isolator **18** is substantially smaller than the attenuation produced by the first isolator **5**. This is explained by the fact that the second isolator **18** can be considered as being a wave-directing interfering element.

It should be observed that the dimensions of the first isolator **5** and/or of the second isolator **18** can be adjusted depending on the intended frequency band.

It should be observed that the greater the conductivity of the material used for making the second isolator **18**, the greater the isolation performance of said second isolator **18**.

With reference to FIG. 18, the RF device **1** also has a second antenna set **20** comprising the third antenna **20b** and a fourth antenna **20a**. In this example, the second antenna set **20** is similar to the first antenna set **2**. Thus, the third antenna **20b** is similar to the second antenna **2b**, and the fourth antenna **20a** is similar to the first antenna **2a**.

The third and fourth antennas **20b** and **20a** lie in the second plane **21** and they are positioned on the support **54**.

A third isolator **33** similar to the first isolator **5** is positioned between the third antenna **20b** and the fourth antenna **20a**. The third isolator **33** is thus arranged to reduce coupling by electromagnetic radiation between the third antenna **20b** and the fourth antenna **20a**.

With reference to FIG. 18, provision is also made for the RF device **1** to have two first antenna sets **2**, two second antenna sets **20**, two first isolators **5**, two third isolators **33**, and four second isolators **18**.

In this example, the RF device **1** rests on a rectangular support **40** of square section (with corners that are slightly rounded). The rectangular support **40** has two first faces **40a**, which two first faces **40a** are parallel with each other; and it has two second faces **40b**, which two second faces **40b** are parallel with each other. The rectangular support **40** thus has four corners **41**, **42**, **43**, and **44**. The rectangular support **40** is thus generally in the shape of a hollow rectangular cylinder.

Preferably, the rectangular support **40** is made out of a material presenting dielectric permittivity that is greater than 1. For example, the rectangular support **40** may be made out of a plastics material or out of a polymer material.

A respective first antenna set **2** is positioned on each of the two first faces **40a** of the rectangular support **40**. A respective first isolator **5** is positioned between the first and second antennas **2a** and **2b** of each of the two first antenna sets **2**.

A respective second antenna set **20** is positioned on each of the two second faces **40b** of the rectangular support **40**. A respective third isolator **33** is positioned between the third and fourth antennas **20b** and **20a** of each of the two second antenna sets **20**.

A respective second isolator **18** is positioned on each of the four corners **41**, **42**, **43**, and **44** of the rectangular support **40**.

First and second antenna groups **G1** and **G2** are defined.

The first antenna group **G1** comprises the first antenna **2a** of each of the two first antenna sets **2** together with the fourth antenna **20a** of each of the two second antenna sets **20**. The first antenna group **G1** thus has four antennas. In this example, the antennas of the group **G1** are dual-band Wi-Fi antennas operating in a so-called 2.4 GHz frequency band and in the so-called 5 GHz frequency band. In another example, the antennas of the group **G1** could be single-band 802.11 technology antennas operating in the so-called 5 GHz frequency band. In another example, the antennas of the group **G1** could be single-band 802.11 technology antennas operating in the so-called 6 GHz frequency band. In yet another example, the antennas of the group **G1** could be

three-band antennas having different subsets of electrical conductors enabling said antennas of the group **G1** to operate simultaneously in the so-called 2.4 GHz frequency band, in the so-called 5 GHz frequency band, and in the so-called 6 GHz frequency band.

The second antenna group **G2** comprises the second antenna **2b** of each of the two first antenna sets **2** together with the third antenna **20b** of each of the two second antenna sets **20**. The second antenna group **G2** thus has four antennas. In this example, the antennas of the group **G2** are single-band Wi-Fi antennas operating in the so-called 6 GHz frequency band.

Also, in the description below, the two first isolators **5**, the two third isolators **33**, and the four second isolators **18** are referred to collectively as an isolation device.

FIGS. 19, 20, 21, and 22 illustrate the role of the first isolator **5**, of the second isolator **18**, and of the third isolator **33** in the RF device **1**. In these figures, the first antenna **2a** belonging to the first antenna group **G1** is transmitting.

In FIGS. 19, 20, 21, and 22, the magnitude of the electric field (in $\text{V}\cdot\text{m}^{-1}$) is represented by three distinct zones. A first zone **Z1** from 0 $\text{V}\cdot\text{m}^{-1}$ to 1000 $\text{V}\cdot\text{m}^{-1}$, a second zone **Z2** from 1000 $\text{V}\cdot\text{m}^{-1}$ to 1400 $\text{V}\cdot\text{m}^{-1}$, and a third zone **Z3** from 1400 $\text{V}\cdot\text{m}^{-1}$ to about 2360 $\text{V}\cdot\text{m}^{-1}$.

In FIGS. 19 and 21, the first antenna **2a** (belonging to the first antenna group **G1**) is transmitting and the other antennas are inactive.

When the isolation device is not present (FIG. 19), a portion of the electric field generated by the first antenna **2a** is picked up by the other antennas, and in particular by the second antenna **2b**.

When the isolation device is present (FIG. 21), the electric field generated by the first antenna **2a** is picked up by the isolation device, and in this example particularly by the first isolator **5**. Coupling by electromagnetic radiation between the antennas of the RF device **1** is thus greatly reduced.

In FIGS. 20 and 22, the second antenna **2b** (belonging to the second antenna group **G2**) is transmitting and the other antennas are inactive.

When the isolation device is not present (FIG. 20), a portion of the electric field generated by the second antenna **2b** is picked up by the other antennas, and in particular by the first antenna **2a** and by the fourth antenna **20a** (FIG. 22).

When the isolation device is present (FIG. 22), the electric field generated by the second antenna **2b** is picked up by the isolation device, and in this example particularly by the second isolator **18**. Coupling by electromagnetic radiation between the antennas of the RF device **1** is thus greatly reduced.

FIG. 23 shows radiation patterns for the antennas of the first antenna group **G1**, and specifically a radiation pattern **46** in the first section **XZ**, a radiation pattern **47** in the second section **YZ**, and a radiation pattern **48** in the third section **XY**. More precisely, in this example, the radiation patterns **46**, **47**, and **48** are average combined-gain radiation patterns.

In the radiation patterns **46**, **47**, and **48**, the continuous line curve corresponds to the combined far field directivity of the antennas of the first antenna group **G1** when the isolation device is not present, and the dashed line curve corresponds to the combined far field directivity of the antennas of the first antenna group **G1** when the isolation device is present.

The radiation patterns **46**, **47**, and **48** reveal that the isolation device serves to make the far field directivity of the antennas of the first antenna group **G1** substantially more uniform.

FIG. 24 shows radiation patterns for the antennas of the second antenna group G2, and specifically a radiation pattern 49 in the first section XZ, a radiation pattern 50 in the second section YZ, and a radiation pattern 51 in the third section XY. More precisely, in this example, the radiation patterns 49, 50, and 51 are average combined-gain radiation patterns.

In the radiation patterns 49, 50, and 51, the continuous line curve corresponds to the combined far field directivity of the antennas of the second antenna group G2 when the isolation device is not present, and the dashed line curve corresponds to the combined far field directivity of the antennas of the second antenna group G2 when the isolation device is present.

The radiation patterns 49, 50, and 51 reveal that the isolation device has limited influence on the far field directivity of the antennas of the second antenna group G2.

The isolation device thus has greater influence on a frequency band in which the antennas of the first antenna group G1 operates than on a frequency band in which the antennas of the second antenna group G2 operate.

The RF device 1 in an embodiment thus serves to respond to the constraints for isolation between the antennas when adjacent frequency bands are in use, while guaranteeing that the radiation pattern of said antennas is omnidirectional (i.e. that the angular distribution of the gain of said antennas is uniform).

Also, the RF device does not require particular antenna technology (e.g. ceramic antennas) and it can be provided using antennas of dimensions that are conventional.

With reference to FIG. 25, the RF device 1 in an embodiment is incorporated in a MIMO system 101 that is itself incorporated in a piece of electronic equipment 100. The MIMO system 101 comprises an RF transmitter 102 and an RF receiver 103 that are both connected to the RF device 1 that may be of various different embodiments, e.g. such as the RF device 1 having the first antenna sets 2 and the second antenna sets 20. The RF transmitter 102 is arranged to deliver electrical signals to the RF device 1. The RF receiver 103 is arranged to receive electrical signals coming from the RF signals received by the RF device 1.

With reference to FIG. 26, the RF device 1 is incorporated in particular in a piece of electronic equipment 100 constituting a residential gateway. In this example, the residential gateway is in the form of a tower.

Naturally, the invention is not limited to the embodiments described, but covers any variant coming within the ambit of the invention as defined by the claims.

The various embodiments of the RF device can be applied in beneficial manner to any electronic equipment that needs to combine multiple RF interfaces (in particular for communication technologies making use of frequency bands that are different, but adjacent) and/or that needs to provide a plurality of transmission paths over a single frequency band, and to do so in a space of small size.

It should be observed that although above the first isolator 5 is T-shaped, it is entirely possible for the first isolator 5 to have some other shape. For example, the first isolator 5 could have three branches that are all electrically conductive and that are arranged in such a manner that the first isolator 5 is Y-shaped. More generally, the shape of the first isolator 5 could be adapted, for example, as a function of performance specified for the RF device 1. The same applies to the third isolator 33, which is similar to the first isolator 5.

In the same manner, although above the second isolator 18 is I-shaped, it is entirely possible for the second isolator 18 to have some other shape. It should be observed that the

shape of the second isolator 18 could be adapted, for example, as a function of performance specified for the RF device 1.

It should be observed that the first isolator 5 is not necessarily fastened to the same support as the support on which the first and second antennas 2a and 2b are fastened. For example, the first isolator 5 could be fastened on a first auxiliary support that is different from the support 4 or the support 54, so as to be held "in the air" between the first and second antennas 2a and 2b. The same applies to the third isolator 33, which is similar to the first isolator 5. The third isolator 33 is not necessarily fastened to the same support as the support on which the third and fourth antennas 20b and 20a are fastened.

In the same manner, the second isolator 18 is not necessarily fastened on a corner of the support 54. For example, the second isolator 18 could be fastened on a second auxiliary support that is different from the support 54, so as to be held in the air, e.g. on the side of the first antenna 2a or of the second antenna 2b that is remote from the first isolator 5.

Also, the first and second antennas 2a and 2b need not necessarily be fastened on the same support. The first and second antennas 2a and 2b could be fastened on respective distinct supports both lying in the same plane.

The invention claimed is:

1. An RF device comprising:
a first antenna set comprising a first antenna and a second antenna, the first and second antennas being planar in shape and both lying in a common first plane, the first antenna being arranged to operate in a first frequency band and the second antenna being arranged to operate in a second frequency band;

a first isolator, the first isolator being planar in shape and lying in the first plane between the first and second antennas, the first isolator having at least one branch that is electrically conductive, the first isolator being electrically floating, the first isolator being arranged to reduce first coupling by electromagnetic radiation between the first and second antennas in the first frequency band and/or in the second frequency band; at least one second isolator having at least one electrically conductive branch, the second isolator being electrically floating, the second isolator being positioned on one side of a particular antenna selected from the first and second antennas, said side of the particular antenna being remote from the first isolator, the second isolator being arranged to correct a modification to the directivity of the particular antenna as caused by the presence of the first isolator.

2. The RF device according to claim 1, wherein the first and second frequency bands are separated by a frequency gap lying in the range approximately 0 MHz to approximately 1 GHz.

3. The RF device according to claim 1, wherein the first antenna set and the first isolator are positioned on a support made out of a dielectric material, the support lying in the first plane.

4. The RF device according to claim 1, wherein the first isolator has first and second branches that are both electrically conductive, the second branch are substantially perpendicular to the first branch and projecting from a central portion of the first branch, a free end of the second branch is open circuit, the first isolator thus is T-shaped.

5. The RF device according to claim 4, wherein the first and second antennas are planar dipole antennas, each is rectangular in shape, the first antenna is arranged to generate

21

a first maximum electric field along a first axis, the second antenna is arranged to generate a second maximum electric field along a second axis, and the first and second axes are substantially parallel to each other.

6. The RF device according to claim 5, wherein the first and second axes are oriented at substantially 45° relative to the second branch.

7. The RF device according to claim 5, wherein the first and second axes are substantially perpendicular to the second branch.

8. The RF device according to claim 5, wherein the first maximum electric field is greater than the second maximum electric field, one end of the first branch of the first isolator is spaced apart from the first axis (E_{2a}) by a distance lying in the range 5 mm to 1.5 cm.

9. The RF device according to claim 4, wherein the first isolator is arranged to reduce the first coupling by electromagnetic radiation to a greater extent in the first frequency band, the first branch of the first isolator has a predefined length that is substantially equal to at least one quarter of a first wavelength λ_A , the first wavelength λ_A being such that:

$$\lambda_A = \frac{c}{v_1 \times \sqrt{\epsilon_r}}$$

wherein v_1 is a first center frequency centered between the maximum frequency and the minimum frequency of the first frequency band, and wherein ϵ_r is the dielectric permittivity of the medium in which the first isolator lies, the medium being a dielectric support or air.

10. The RF device according to claim 4, wherein the first isolator is arranged to reduce the first coupling by electromagnetic radiation in equal manner in the first and second frequency bands, the first branch of the first isolator has a predefined length that is substantially equal to at least one quarter of a first wavelength λ_A , the first wavelength λ_A being such that:

$$\lambda_A = \frac{c}{\frac{v_1 + v_2}{2} \times \sqrt{\epsilon_r}}$$

wherein v_1 is a first center frequency centered between the maximum frequency and the minimum frequency of the first frequency band, wherein v_2 is a second center frequency centered between the maximum frequency and the minimum frequency of the second frequency band, and wherein ϵ_r is the dielectric permittivity of the medium in which the first isolator lies, the medium being a dielectric support or air.

11. The RF device according to claim 9, wherein the second branch of the first isolator has a predefined length that is substantially equal to one quarter of the first wavelength λ_A .

12. The RF device according to claim 4, wherein the first branch of the first isolator has a width that is predefined so that the characteristic impedance of said first branch is substantially equal to the characteristic impedance of one antenna selected from the first and second antennas, the second branch of the first isolator has a width that is predefined so that the characteristic impedance of said second branch is substantially equal to the characteristic impedance of the antenna selected from the first and second antennas.

22

13. The RF device according to claim 4, wherein the first branch of the first isolator has a width that is predefined so that the characteristic impedance of said first branch lies substantially in the range 75Ω to 120Ω, the second branch of the first isolator has a width that is predefined so that the characteristic impedance of said second branch lies substantially in the range 75Ω to 120 Ω.

14. The RF device according to claim 1, wherein the first isolator has three branches that are all electrically conductive and that are arranged in such a manner that said first isolator is Y-shaped.

15. The RF device according to claim 1, wherein the second isolator has a single electrically conductive branch, said isolator thus having a shape that is longitudinal.

16. The RF device according to claim 1, comprising a third antenna extending in a second plane, wherein the second isolator also is arranged to reduce second coupling by electromagnetic radiation between the third antenna and the particular antenna over a particular frequency band in which the particular antenna operates and over a third frequency band in which the third antenna operates.

17. The RF device according to claim 1, wherein the second isolator is arranged to reduce the second coupling by electromagnetic radiation to a greater extent in the particular frequency band, the single branch of the second isolator has a predefined length that is substantially equal to half a second wavelength λ_B , the second wavelength λ_B being such that:

$$\lambda_B = \frac{c}{v_{\#} \times \sqrt{\epsilon_r}}$$

wherein $v_{\#}$ is a particular center frequency centered between the maximum frequency and the minimum frequency of the particular frequency band, and wherein ϵ_r is the dielectric permittivity of the medium in which the second isolator lies, the medium being a dielectric support or air.

18. The RF device according to claim 15, wherein the second isolator is arranged to reduce the second coupling by electromagnetic radiation in equal manner in the particular frequency band and in the third frequency band, the single branch of the second isolator has a predefined length that is substantially equal to half a second wavelength λ_B , the second wavelength λ_B being such that:

$$\lambda_B = \frac{c}{\frac{v_{\#} + v_3}{2} \times \sqrt{\epsilon_r}}$$

wherein $v_{\#}$ is a particular center frequency centered between the maximum frequency and the minimum frequency of the particular frequency band, wherein v_3 is a third center frequency centered between the maximum frequency and the minimum frequency of the third frequency band, and wherein ϵ_r is the dielectric permittivity of the medium in which the second isolator lies, the medium being a dielectric support or air.

19. The RF device according to claim 15, wherein the branch of the second isolator has a width that is predefined so that the characteristic impedance of said branch is substantially equal to the characteristic impedance of an antenna selected from the particular antenna and the third antenna.

23

20. The RF device according to claim **15**, wherein the branch of the first isolator has a width that is predefined so that the characteristic impedance of said branch lies substantially in the range 75Ω to $120\ \Omega$.

21. The RF device according to claim **16**, wherein the second isolator is situated in the proximity of an intersection between the first and second planes.

22. The RF device according to claim **21**, wherein the second isolator is positioned in an intersecting plane that intersects the first and second planes.

23. The RF device according to claim **21**, wherein the second isolator forming a rounded corner between the first and second planes.

24. The RF device according to claim **16**, wherein the first and second planes being perpendicular.

25. The RF device according to claim **16**, comprising a second antenna set comprising the third antenna and a fourth antenna, wherein the second antenna set being similar to the first antenna set, and also including a third isolator similar to the first isolator and positioned between the third and fourth antennas.

24

26. The RF device according to claim **25**, comprising a support having four faces comprising two mutually parallel first faces and two mutually parallel second faces, two first antenna sets each positioned on a distinct first face, and two second antenna sets each positioned on a distinct second face, wherein the RF device further comprising two first isolators each positioned between the first and second antennas of a distinct first antenna set, two third isolators each positioned between a third antenna and a fourth antenna of a distinct second antenna set, and four second isolators each positioned in a distinct corner of the support.

27. A MIMO system including the RF device according to claim **25** together with an RF transmitter and an RF receiver both connected to the first and second antenna sets of said RF device.

28. Electronic equipment including a MIMO system according to claim **27**.

29. Electronic equipment according to claim **28**, wherein the electronic equipment is a residential gateway.
